FIG. 2.

William Walter Smout

INVENTOR:

By *Otis H. Smith*
his Attorney.

UNITED STATES PATENT OFFICE

1,924,420

PEN

William Walter Smout, Rhyl, Wales

Application September 23, 1932, Serial No.
634,499, and in Great Britain April 30, 1932

5 Claims. (Cl. 120—42)

This invention concerns improvements in or relating to pens, and has particular reference to fountain pens.

Inconveniences frequently experienced by business men and others due to the lack of blotting paper with which to blot writing on cheques and so forth, and it is the primary object of this invention to provide means whereby this inconvenience may be obviated.

10 Referring to the drawing:—

Figure 1 is a part longitudinal sectional elevation of a fountain pen having this invention applied thereto.

Figure 2 is a perspective view of the same with the top cap removed.

In the construction illustrated the blotting roller 8 is pivotally mounted upon a spindle 11, the reduced ends 12 of this spindle engaging in apertures in the parallel arms 13 of a substantially U shaped frame.

The frame is pivotally mounted upon a rivet 14 secured in aligned holes in the connecting or base portion 15 of the frame, and a projecting arm 16 of a supporting bracket 17 secured to 25 the cap.

The bracket 17 is attached to the cap 2 by means of an integral projection 18 inserted through an aperture in the end of the cap and riveted over on the inside, the arm 16 extending parallel to the axis of the cap.

The yoke is provided with a further upstanding arm 19 disposed diametrically opposite to the arm 16, and whilst this arm has no direct connection to the roller or to the supporting frame therefor it serves to locate the roller and prevent the latter moving out of alignment with the axis of the pen except any movement around the pivot 14 when it is desired to use the roller.

In this construction operation of the device is simplified since the interference with the operation of the roller by parts of the supporting structure therefor is reduced to a minimum, and the blotting roller may be used in a number of positions with respect to the axis of the pen as will be apparent from the perspective view shown in Figure 2.

The operation of removing or renewing the blotting roller is greatly facilitated since it is only necessary to distort one of the arms 13 out of engagement with the reduced end 12 of the spindle 11, the roller together with the spindle being then free to leave the frame. A new roller can then be positioned upon the spindle and can be 55 inserted in the frame by passing through the

steps in the opposite sequence to that described above.

In order to facilitate the above described operation the frame is preferably constructed of slightly springy material, or the arms are formed with a certain amount of rigidity or spring so that when distorted out of the normal position to remove the roller and the spindle the arms of the frame move back into their original positions when the distorting force is removed.

The pivotal connection between the frame 15 and the arm 16 of the supporting yoke is preferably made fairly stiff in operation so that when moved into the normal position as shown in Figure 1 the roller tends to retain its position against the action of gravity when the pen is held in a more or less horizontal position.

When it is desired to use the roller it is only necessary to press the outer projecting end lightly into contact with the surface to be blotted when the roller moves about the rivet 14 into the position shown in Figure 2.

The blotting roller may if desired be provided with an inner sleeve or liner 9 of metal to form a bearing for the spindle 11.

What I claim then is:—

1. In combination a cap for a fountain pen, a blotting roller, a carrier member for said blotting roller, said carrier comprising a frame of U shape, pivots in the arms of said U shaped frame, said blotting roller being rotatably mounted in said pivots, a supporting bracket for said carrier member, an arm on said supporting bracket extending parallel to the axis of the cap, a pivot at the projecting end of said arm, said carrier member being rotatable on said pivot about an axis at right angles to the axis of the blotting roller, and a secondary cap adapted to fit removably on said fountain pen cap and to enclose said blotting roller, carrier and supporting bracket.

2. In combination a cap for a fountain pen, a blotter roller, a carrier member for said blotting roller, said carrier comprising a frame of U shape, pivots in the arm of said U shaped frame, said blotting roller being rotatably mounted in said pivots, a supporting bracket for said carrier, an arm on said bracket extending parallel to the axis of the cap, a pivot pin at the projecting end of said arm, said pivot pin engaging the base of said U shaped frame so that the carrier member is rotatable about an axis at right angles to the axis of said blotting roller, and a secondary cap adapted to fit removably on said fountain pen cap and to enclose said blotting roller, carrier and supporting bracket.

3. In combination a cap for a fountain pen, a blotting roller, a carrier member for said blotting roller, said carrier comprising a U shaped frame, a spindle mounted between the arms of said U shaped frame, said blotting roller being rotatably mounted on said spindle, a supporting bracket for said carrier, said bracket comprising a base portion for attachment to said cap and a projecting arm extending from said base portion parallel to the axis of the cap, a pivot at the projecting end of said arm, said carrier member being rotatable on said pivot about an axis at right angles to the axis of the blotting roller, an integral projection on the base portion of said bracket for engagement in an aperture in the end of said cap, and a secondary cap adapted to fit removably on said fountain pen cap and to enclose said blotting roller, carrier and supporting bracket. 80
- 10 4. In combination a cap for a fountain pen, a blotting roller, a carrier member for said blotting roller, said carrier comprising a frame of U shape, a spindle mounted between the arms of said U shaped frame, said blotting roller being rotatably mounted on said spindle, a supporting bracket for said carrier, said supporting bracket comprising a base portion for attachment to said cap and two projecting arms extending parallel to the axis of the cap and engaging said base portion at diametrically opposite position thereon, one of said arms being substantially longer than the other, a pivot at the projecting end of said longer arm, said carrier member being rotatable on said pivot about an axis at right angles to the axis of the blotting roller, said shorter arm locating the roller in the out of use position, an integral projection on the underside of said base portion for engagement in an aperture in the end of said cap, and a secondary cap adapted to fit removably on said fountain pen cap and to enclose said blotting roller, carrier and supporting bracket. 85
- 15 20 5. In combination a cap for a fountain pen, a blotting roller, a carrier member for said blotting roller, said carrier comprising a frame of U shape, a spindle mounted between the arms of said U shaped frame, said blotting roller being rotatably mounted on said spindle, a supporting bracket for said carrier, said supporting bracket comprising a base portion for attachment to said cap and two projecting arms extending parallel to the axis of the cap and engaging said base portion at diametrically opposite position thereon, one of said arms being substantially longer than the other, a pivot at the projecting end of said longer arm, said carrier member being rotatable on said pivot about an axis at right angles to the axis of the blotting roller, said shorter arm locating the roller in the out of use position, an integral projection on the underside of said base portion for engagement in an aperture in the end of said cap, and a secondary cap adapted to fit removably on said fountain pen cap and to enclose said blotting roller, carrier and supporting bracket. 90
